M. H. CARLSON.
AUTOMOBILE LICENSE NUMBER TAG.
APPLICATION FILED DEC. 3, 1913.

1,152,076.

Patented Aug. 31, 1915.

UNITED STATES PATENT OFFICE.

MARTIN H. CARLSON, OF GIBBON, NEBRASKA.

AUTOMOBILE LICENSE-NUMBER TAG.

1,152,076.

Specification of Letters Patent. Patented Aug. 31, 1915.

Application filed December 3, 1913. Serial No. 804,425.

To all whom it may concern:

Be it known that I, MARTIN H. CARLSON, a citizen of the United States, residing at Gibbon, in the county of Buffalo, State of Nebraska, have invented certain new and useful Improvements in Automobile License-Number Tags; and I do hereby declare the following to be a full, clear, and exact description of the invention, such as will enable others skilled in the art to which it appertains to make and use the same.

This invention relates to improvements in license number holders adapted for attachment to automobiles.

15 The principal object of the invention is to provide a simple construction whereby the license number can be as readily seen at night as in the day time.

Another object is to provide a device of 20 this character which can be quickly and easily opened to such an extent that ready and easy access can be gained to the interior thereof.

Other objects and advantages will be apparent from the following description, when taken in connection with the accompanying drawings.

In the drawings: Figure 1 is an elevation of my license holder. Fig. 2 is an end elevation. Fig. 3 is a vertical transverse sectional view on the line 3—3 of Fig. 1. Fig. 4 is a longitudinal sectional view on the line 4—4 of Fig. 2. Fig. 5 is a transverse sectional view showing the holder in position to replace the license number. Fig. 6 is a top plan view.

Referring particularly to the accompanying drawings, 10 represents an elongated plate of flexible metal which is bent arcu-

40 ately in the form of a trough. Hinged to the upper edge of the plate 10 is a door 10' through which are cut openings in representation of numbers and letters, these numbers and letters forming the 45 license number and State. Secured to the upper portion of the door 10', and near the upper edge thereof, are the brackets 12, each of the brackets carrying a set screw 13, and each screw carrying an angle plate 14 on its lower end. Secured to the inner 50 side of the door 10' near the lower end, are the angle brackets 15. A plate of glass 16 has its lower edge resting on the brackets 15, and its upper edge held by the angle plates 14. This glass plate is disposed in rear of the door 10', and fits snugly there-

against. The end and upper edge portions of the door 10' are provided with the flanges 11. By turning these screws 13, the angle plates 14 will be forced against the upper longitudinal edge of the glass to firmly hold the same in position.

Hinged to the rear portion at each end of the curved plate 10 is a door 17, this door having the laterally directed curved flanges 18 which embrace the ends of the curved plate. The free edge of each of the doors 17 carries a pivoted latch member 20 which engages between a pair of keepers 21 carried by the door 10' of the holder. Thus 70 when the doors are closed and fastened, the plate 10 is held in its curved position. This front door 10' of the holder, is hinged to the upper edge of the plate 10, as before mentioned and has a flange 23 on its lower 75 edge which extends under the lower edge of the plate 10, this flange being provided with a plurality of notches 24 arranged to receive the bolts 25 carried by the lower edge of the plate 10. These bolts carry the nuts 80 26 which when tightened clamp the flange 23 firmly against the edge of the plate 10. In the rear of the plate 10 are formed openings 27 for the introduction of electric light sockets 28. Also carried by the rear of the 85 plate 10 are socketed members 29 which are arranged for engagement with brackets 30 carried by the automobile to suspend the license number holder in proper position.

Secured to the upper edge of the plate 10 90 and extending vertically therefrom is a plate 31, provided with an opening 32 for the introduction of the split resilient shouldered head 34 of an electric light socket 35, which is arranged to carry a red lamp 36. 95

When the plate 31 is used in connection with the holder, the holder is particularly adapted for use at the rear of the automobile, but when the same is used at the front of the automobile, this plate is omitted. 100

From the foregoing, it will readily be seen that I have provided a simple device of this character and one in which the license number plate, and the holder are securely held in position.

105 What is claimed is:

A license number tag, comprising an elongated flexible metallic plate bent on its longer dimension into trough-like form, a front plate hinged to one of the long edges 110 and having its free edge detachably secured to the other longer edge of the plate,

said front plate having openings in the form of characters therethrough and flanges on its four sides, semi-circular doors hinged to intermediate portions of the 5 shorter edge portions of the flexible plate, a pivoted locking means carried by each of the semi-circular doors, and laterally directed flanges carried by the semi-circular doors and overlapping the corresponding

edges of the flexible plate, whereby the body 10 portion is held in trough-like form.

In testimony whereof, I affix my signature, in the presence of two witnesses.

MARTIN H. CARLSON.

Witnesses:

CHESTER HOLLOWAY,
FRED CARLSON.
